UNITED STATES PATENT OFFICE.

ALPHEUS L. KISER, OF KNOXVILLE, TENNESSEE.

PROJECTING APPARATUS.

Application filed September 24, 1924. Serial No. 739,564.

To all whom it may concern:

Be it known that I, ALPHEUS L. KISER, a citizen of the United States, residing at Knoxville, in the county of Knox and State of Tennessee, have invented certain new and useful Improvements in Projecting Apparatus, of which the following is a specification.

This invention relates to a projecting apparatus, designed primarily for advertising purposes, but it is to be understood that an apparatus in accordance with this invention can be employed for any purposes wherein it is found applicable, and the invention has for its object to provide, in a manner as hereinafter set forth, a projecting apparatus including means for displaying advertisements by means of slides which are automatically changed at predetermined intervals, or rather, which are intermittently shifted the required distance for positioning the slides successively to have the advertisement or other matter carried thereby projected upon a screen or wall for display purposes.

A further object of the invention is to provide, in a manner as hereinafter set forth, a machine of such class provided with means for surrounding the displayed advertisement, picture, view or the like by a colored flashing border.

Further objects of the invention are to provide a projecting apparatus, in a manner as hereinafter set forth, which is simple in its construction and arrangement, strong, durable, compact, efficient and convenient in its use, readily assembled and comparatively inexpensive to manufacture and operate.

With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:—

Figure 1 is a perspective view of a project-

ing apparatus in accordance with this invention.

Figure 2 is a longitudinal sectional view 55 of a projecting apparatus in accordance with this invention, looking towards one side of the mechanism.

Figure 3 is a similar view, looking towards 60 the other side of the mechanism.

Figure 4 is a horizontal sectional view of the apparatus.

Figure 5 is a fragmentary view, with the elements disassembled, showing the means for securing a slide with the carrier. 65

Figure 6 is a side elevation of the apparatus showing the adaptation thereof with respect to a screen or other surface upon which the advertisement or the like surrounded by a border is projected. 70

Figure 7 is an elevation of the border producing device.

Figure 8 is a fragmentary view, in front elevation, of a condensing lens casing.

Referring to the drawings in detail, a 75 projecting apparatus in accordance with this invention, comprises a depending flanged rectangular base 1, to which is secured a housing, consisting of a pair of side walls 2, 3, a top 4, a front wall 5 and a rear wall 6. The front wall 5 is of greater height 80 than the rear wall 6. The top edge of each of the side walls 2, 3, is oppositely inclined and upon said edges is secured the top 4, which is inclined to conform to the contour 85 of said edges. The top 4 projects laterally from the front wall 5, rear wall 6, and side walls 2, 3, and has depending side flanges 4'. Each of the side walls is formed near its top with a row of perforations 7, providing 90 outlets for hot air, and near its bottom with a row of openings 8, forming inlets for cold air. The walls 2, 3, 5 and 6, are secured in any suitable manner against the edges of the base 1. 95

The side wall 2 is formed with enlarged openings 9, 9', to provide for access to the interior of the housing, and the said openings are closed respectively by hinged doors 10, 10', and the former is locked interiorly of 100 the housing, as at 11, and the latter exteriorly, as at 11'. The wall 3 is provided with an opening 12', closed by means of a hinged door 12'' locked by any suitable

means. Above the doors 10, 10' and 12' deflectors 13' are arranged, and below the doors and above the openings 8 deflectors 13'' are positioned. The deflectors 18' and 13'' are 5 fixedly secured to the sides of the housing.

The housing as well as the base 1, can be of any suitable size desired and constructed of any suitable material, preferably the base is constructed of 92% aluminum and 8% 10 copper and is of the necessary weight to insure for a solid foundation for the apparatus. Preferably the housing is constructed of sheet metal of the desired weight.

The front wall 5 is provided at a point 15 between its transverse center and its upper end with an opening 12, and at a point between its transverse center and its lower end with an opening 13, and the purpose of the openings will be presently referred to.

Secured to the base 1, centrally thereof, 20 is a vertical support, referred to generally by the reference character 14 and formed of a lower portion 15, an inwardly extending intermediate portion 16, which is disposed 25 at right angles with respect to the lower portion 15, and said support further includes an upper portion 17, having an opening 20 at its upper end for the reception of one end 30 of a carrier shaft 21. The lower portion 15 of the support is formed with a flange 18, through which extends the hold-fast device 19 for fixedly securing the support to the base 1.

Secured to the base 1, centrally thereof, 35 and opposing the support 14, is a vertical support, referred to generally by the reference character 24, and which includes a lower portion 25, an intermediate portion 26 which extends towards the upper portion 17 40 of the support 14, and said support 24 further includes a vertically extending portion 27, formed at its upper end with a bearing 28 for the reception of the other end of the carrier shaft 22, and with the latter projecting laterally therefrom.

That end of the shaft 22, which projects from the bearing 28, is indicated at 22', Figure 4, and has clamped thereon a hanger 28', having adjustably connected with its lower end, as at 28'' a suspension bar 28''', Figure 2.

Fixedly secured to the upper portion 27 55 of the support 24 and extending towards the front wall 2, is a platform 29, which supports a light element 30 in the form of an incandescent electric lamp. The lamp 30 is secured in a socket element 31, which is connected with the platform 29, and leading to said socket element 31 are circuit wire connections 32, 33. Hold-fast devices 35 are provided for securing the platform 29 to the upper portion 27 of the support 24.

Adjustably secured to bar 28''' as at 34, 60 is a bracket arm 36, which carries a reflector holder 37, and connected with the holder 37

is a reflector 38, which opposes, as well as being arranged rearwardly with respect to the lamp 30. The reflector 38 is spaced from the lamp 30 and is arranged in alignment with respect to a casing 39, provided with a 70 condensing lens 39', positioned forwardly of and arranged in proximity to the lamp 30. The casing 39 is mounted on the upper end of a vertical supporting standard 40, which is secured to the base 1.

Carried by the head 40', of a standard 75 40'', is an adjustable focusing mount 41, which opposes the opening 12, and is arranged in alignment with respect to the casing 39, lamp 30 and reflector 38. The 80 mount 41 is provided with a suitable focusing element.

The projecting apparatus includes an intermittently operable carrier comprising a hub 42, having formed integral therewith a 85 series of spokes 43, which are detachably connected to an annular rim 44. One side of the hub 42 is extended, as at 45, and the free end of the extension 45 is positioned in proximity to the bearing 28 at the upper end 90 of the portion 27 of the support 24. The carrier is arranged in close proximity to the standard 14 and the spokes 43 are flush with one edge but spaced from the other edge of the rim 44. The width of the body of the 95 rim 44 is such whereby the rim will not oppose the lamp 30 or the condensing lens, or the spiral focusing mount so as not to interfere with the projecting operation when the apparatus is operated for display purposes. 100 The hub 42 revolves on the shaft 22.

The carrier further includes a circular series of slide holders, and the said slide holders are arranged in pairs and each pair is adapted to support a slide. The slide 105 holders are spaced from each other and each pair of holders not only supports a slide, but spaces one slide from another but also includes means to provide for the intermittent revolving of the carrier. Each slide 110 holder of each pair, see Figure 5, consists of a semi-circular body portion 46, which is disposed at right angles with respect to the rim, provides the abutment for a slide and if formed on its inner edge with a pair of laterally extending apertured lugs 47, through which extend hold-fast devices 48, see Figure 4, for securing the holders upon the outer face of the rim 44. Formed integral with one side of the body portion 46, and extending in the direction of, as well as positioned at right angles with respect to and between said lugs 47, is an abutment member 49 engaged by means to be hereinafter referred to, to provide for the intermittent shifting of the carrier. Formed integral 115 with the body portion 46, on that side opposite to which the abutment member 49 is formed integral, is a holding arm 50, rabbed at each side of its inner face to pro- 120 125 130

- vide a shoulder 51 and a seat 52. The shoulder 51 and seat 52 of each arm 50, extend lengthwise thereof. The thickness of the arm 50 is less than the height of the body 5 portion 46 and the outer face of said arm is flush with the outer edge of the body portion 46. The arm 50, at the longitudinal center thereof, is formed with a pair of spaced openings 53.
- 10 Cooperating with the arm 50, for the purpose of securing one side of a pair of slides therewith, is a flat clamping member 54, which is of a width greater than the width of the arm 50 and is provided with a 15 pair of screws 55, which extend down through the openings 53 and have mounted on their lower ends retaining nuts 57 for the purpose of clamping the member 54 against the arm 50, thereby securing the 20 slides which are mounted on the seats 52, to the arm 50. The rim 44 is provided with openings 58, for the passage of the hold-fast devices 48. The outer end of the member 54 is curved or inclined away from the 25 arm 50, as at 59, to provide for the convenient mounting of a slide.
- One side edge of the rim 44 is formed with spaced sockets 60, see Figure 4, in which successively engages a spring controlled retaining member 61, carried by the 30 intermediate portion 16 of the support 14, for the purpose of preventing the accidental shifting of the rim 44 after it has been moved the desired distance.
- 35 Supported by the base 1, is an electric motor 62, having the shaft thereof indicated at 63, and connected with the motor 62 are circuit wires 64. Connected to the shaft 63, is a transmission shaft 66 provided with 40 a fan 63'.
- Arranged upon the base 1, at one side of the motor 63, is a gear box 65 from which projects the shaft 66. Arranged within the box 65 is a suitable gear transmission, not shown, for operating a shaft 67 which carries a sprocket pinion 68, which drives an endless chain 70, travelling over a pinion 71, carried by a shaft 72, projecting from a gear box 73, in which is arranged a 45 suitable gear drive, not shown, operated from the shaft 72 and actuating a transmission shaft 81, supported in and projecting from a standard 82. The chain 70 also travels over a guide 74, carried by a support 75. The guide 74 elevates the intermediate portion of the upper part of the chain 70. Secured to the chain 70 is a lug 76, adapted to successively engage the abutment members 49 for the purpose of intermittently revolving the carrier to position a slide in operative relation with respect to the condensing lens and further between said lens and the spiral focusing mount, so that the matter carried by the slide can be projected for display purposes. When the 50 carrier is shifted to arrange a slide in operative relation with respect to the condensing lens, the retaining member 61 engages in a pocket 60 and holds the carrier from accidental shifting, and the carrier will be held 70 until the lug 76 engages with an abutment member 48 for the purpose of shifting the carrier a predetermined distance. The lug 76 will engage with an abutment member 48 when the chain 70 arrives at its highest 75 point, then when the chain continues to travel, the lug bearing against the member 48 will shift the carrier until the lug 76 moves clear of the member 48. The direction of travel of the chain 70 is indicated by 80 the arrow in Figure 2.
- For the purpose of providing circulation of air through the housing for a cooling effect, the fan 78 on the shaft 66 is employed.
- Secured to the base 1, forwardly of the gear box 73, and to one side of the shaft 81, is a post 83 upon which is adjustably mounted a forwardly extending bracket 84 for supporting the socket 85 of a forwardly disposed lamp 86. Connected to the bracket 90 84, is a vertically disposed suspension arm 87 for a reflector 88, which is arranged at the rear of the lamp 86.
- Supported forwardly of the lamp 86, is a box 89, provided with a pair of condensing lenses 90, which are in alignment with the lamp 86. A color effect obtaining element in the form of a transparent sheet of any suitable color, indicated at 91, is arranged at the front of the box 89 and 100 positioned forwardly of said element 91, as well as being secured to the box 89, is a plate 92, formed with a rectangular row of spaced openings 93.
- Positioned forwardly of the box 89, and 105 in proximity to the plate 92, is an inverted yoke-shaped supporting bracket 94, secured as at 95 to the base 1. A bearing 96 is secured to the top of the bracket 94 and in which is journalled a shutter shaft 97 carrying a winged shutter 98, for intermittently and successively opening and closing the openings 93. The shaft 97 is operated from the shaft 81 and for such purpose the shaft 97 is provided with a pinion 99 driven 110 from a pinion 100, on the shaft 81, through the medium of a transmission chain 101. See Figure 7. Circuit wires 102 are provided for the lamp 86.
- The lamp 86, condensing lenses 90, element 91, apertured plate 92 and winged shutter 97 provide for the surrounding of the displayed advertising or like matter with a border having a flashing effect.
- The lamp 30 is a one thousand watt lamp, 120 and the lamp 86 is a four hundred watt lamp. Secured to the end wall 5 and in alignment with the lamp 30, is a light directing tube 103. Secured to the wall 5 and in alignment with the lamp 86, but ex- 130

tending at a slight upward inclination, is a light directing tube 104. The tubes 103, 104 project forwardly from the wall 5. The manner in which the light rays are directed is shown in Figure 6. By reference to the latter, a screen or other surface upon which the matter is displayed is designated 105. The tubes 103, 104 register respectively with the openings 12, 13.

10 A switch for the lamps is indicated at 106, and a switch for the motor at 107, to enable the opening or closing of the lamp circuits independent of the motor circuits.

15 Projection is made through two focus lenses arranged rearwardly with respect to the slides and through a spiral focusing mount arranged forwardly of the slide and which will display the advertisement carried by the slide on a screen at varying distances 20 from the apparatus.

25 The holders may be arranged in pairs so that each pair will support a slide 80, or each holder of each pair of holders can be utilized to support the sides of a pair of opposed slides. The holders can be so set up with respect to the rim, as to provide for the desired interval between the intermittent shifts of the carrier, and although the preferred embodiment of the invention is as 30 illustrated and described, yet it is to be understood that changes in the details of construction and arrangement can be had which will fall within the light of the invention as claimed.

35 What I claim is:—

1. A projecting apparatus comprising a carrier including a rim, a series of spaced slide abutments disposed throughout said rim, a pair of apertured lugs extended from one side of each of said abutments and adapted to be secured to the rim, an abutment member overlapping the rim and formed integral with the said side of each of said abutments, a holding arm extended from the other side of each of said slide abutments, said arm rabbeted on its inner face to provide a seat, a slide clamping member mounted on said arm, and means for detachably clamping said member to said arm to secure a slide thereto.

2. A projecting apparatus comprising a carrier including a rim, a series of spaced slide abutments disposed throughout said rim, a pair of apertured lugs extended from one side of each of said abutments and adapted to be secured to the rim, an abutment member overlapping the rim and formed integral with the said side of each of said abutments, a holding arm extended from the other side of each of said slide abutments, said arm rabbeted on its inner face to provide a seat, a slide clamping member mounted on said arm, means for detachably clamping said member to said arm to secure a

slide thereto, and means successively engaging with said abutment members for intermittently shifting said carrier. 65

3. A projecting apparatus comprising a carrier including a rim, a series of spaced slide abutments disposed throughout said rim, a pair of apertured lugs extended from one side of each of said abutments and adapted to be secured to the rim, an abutment member overlapping the rim and formed integral with the said side of each of said abutments, a holding arm extended from the other side of each of said slide abutments, said arm rabbeted on its inner face to provide a seat, a slide clamping member mounted on said arm, means for detachably clamping said member to said arm to secure a slide thereto, said rim having one side edge thereof formed with a series of spaced sockets, each positioned between opposed lugs of a pair of slide holders, means successively engaging with said abutment members for intermittently shifting said carrier, and a spring controlled element successively engaging in said sockets for intermittently retaining said carrier in the position to which it has been shifted. 70 75 80 85 90 95

4. A projecting apparatus comprising a carrier including a rim, a series of spaced slide abutments disposed throughout said rim, a pair of apertured lugs extended from one side of each of said abutments and adapted to be secured to the rim, an abutment member overlapping the rim and formed integral with the said side of each of said abutments, a holding arm extended from the other side of each of said slide abutments, said arm rabbeted on its inner face to provide a seat, a slide clamping member mounted on said arm, means for detachably clamping said member to said arm to secure a slide thereto, a shaft forming a part of said carrier, means successively engaging with said abutment members for intermittently shifting said carrier, a pair of supports for said shaft, a platform extended forwardly from one of said supports, a reflector secured with the upper end of the last mentioned support, a light element mounted on the platform and arranged forwardly of the reflector, a condensing element arranged forwardly of said light element, and a focusing element arranged forwardly of said condensing element, and said slide holders positioned to extend from the rim whereby during the operation of the carrier the slide holders will be positioned between said condensing element and said focusing element. 100 105 110 115 120

5. A projecting apparatus comprising a carrier including a rim, a plurality of slide holders carried thereby and each including a body portion provided with apertured lugs for connection with said rim and further provided with an abutment member and a hold-

ing arm extending in an opposite direction with respect to said abutment member, said holding arm being rabbeted to provide a slide seat, a connecting member positioned 5 in parallelism with respect to said holding arm, means for detachably connecting said clamping member with said arm for securing a slide to the holder when mounted on said seat, means successively engaging with 10 said abutment members for intermittently shifting said carrier, a shaft forming a part of said carrier, a pair of supports for said shaft, a platform extended forwardly from one of said supports, a reflector secured 15 with the upper end of the last mentioned support, a light element mounted on the platform and arranged forwardly of the reflector, a condensing element arranged forwardly of said light, and a focusing element 20 arranged forwardly of said condensing element, said slide holders positioned to extend from the rim whereby during the operation of the carrier the slide holders will be positioned between said condensing element 25 and said focusing element.

6. A projecting apparatus comprising a carrier including a rim, a plurality of slide holders carried thereby and each including a body portion provided with apertured lugs 30 for connection with said rim and further provided with an abutment member and a holding arm extending in an opposite direction with respect to said abutment member, said holding arm being rabbeted to provide 35 a slide seat, a connecting member positioned in parallelism with respect to said holding arm, means for detachably connecting said clamping member with said arm for securing a slide to the holder when mounted on 40 said seat, means successively engaging with said abutment members for intermittently shifting said carrier, said rim having one edge provided with a plurality of pockets, a spring controlled element successively engaging in said pockets for intermittently retaining 45 said carrier in the position to which it has been shifted, a shaft forming a part of said carrier, a pair of supports for said shaft, a platform extended forwardly from 50 one of said supports, a reflector secured with the upper end of the last mentioned support, a light element mounted on the platform and arranged forwardly of the reflector, a condensing element arranged forwardly of 55 said light, and a focusing element arranged forwardly of said condensing element, said slide holders positioned to extend from the rim whereby during the operation of the carrier the slide holders will be positioned 60 between said condensing element and said focusing element.

7. A projecting apparatus comprising a reflector element, a light element arranged forwardly of the reflector element, a condensing element arranged forwardly of the light element, a focusing element arranged forwardly of the condensing element, an intermittently operable carrier including an 65 annular rim provided with a plurality of laterally extending spaced slide holders each formed with an abutment member overlapping and extending at right angles with respect to one side of said rim, means suc-

light element, a focusing element arranged forwardly of the condensing element, an intermittently operable carrier including an annular rim provided with a plurality of laterally extending slide holders each formed 70 with an abutment member extending overlapping the outer side of said rim, and means successively engaging with the abutment members for intermittently operating the carrier to successively position the slides 75 supported by the holders between the condensing and focusing elements.

8. A projecting apparatus comprising a reflector element, a light element arranged forwardly of the reflector element, a condensing element arranged forwardly of the light element, a focusing element arranged forwardly of the condensing element, an intermittently operable carrier including an annular rim provided with a plurality of 85 laterally extending slide holders each formed with an abutment member overlapping the outer side of said rim, said rim having one edge formed with a series of equidistant sockets, means successively engaging 90 with the abutment members for intermittently operating the carrier to successively position the slides supported by the holders between the condensing and focusing elements, and a spring controlled element successively and detachably engaging in the 95 sockets of the rim for maintaining the carrier in position when shifted.

9. A projecting apparatus comprising a reflector element, a light element arranged 100 forwardly of the reflector element, a condensing element arranged forwardly of the light element, a focusing element arranged forwardly of the condensing element, an intermittently operable carrier including an 105 annular rim provided with a plurality of laterally extending spaced slide holders each formed with an abutment member overlapping one side of said rim, means successively engaging with the abutment members 110 for intermittently operating the carrier to successively position the slides supported by the holders between the condensing and focusing elements, a housing inclosing said carrier and said elements and having the 115 focusing element projecting therefrom, and means to provide a circulation of air through said housing.

10. A projecting apparatus comprising a reflector element, a light element arranged 120 forwardly of the reflector element, a condensing element arranged forwardly of the light element, a focusing element arranged forwardly of the condensing element, an intermittently operable carrier including an 125 annular rim provided with a plurality of laterally extending spaced slide holders each formed with an abutment member overlapping and extending at right angles with respect to one side of said rim, means suc-

cessively engaging with the abutment members for intermittently operating the carrier to successively position the slides supported by the holders between the condensing and focusing elements, said rim having one end provided with spaced sockets, a spring controlled element successively and detachably engaging in the sockets of the rim for maintaining the carrier in position when shifted, a housing inclosing said carrier and said elements and further having said focusing element projecting therefrom, and means to provide for a circulation of air through said housing.

11. A projecting apparatus comprising a carrier including a rim, a series of spaced slide abutments disposed throughout said rim, a pair of apertured lugs extended at right angles to and integral with one side of each of said abutments and adapted to be secured to the rim, an abutment member carried by and disposed at right angles with respect to the said side of each of said abutments and overlapping the rim, a holding arm extended at right angles to and from the other side of each of said slide abutments, said arm rabbeted on its inner face at each side thereof to provide a seat, a slide clamping member mounted over said

15. 12. A projecting apparatus comprising a carrier including a rim, a series of spaced slide abutments disposed throughout said rim, a pair of apertured lugs extended at right angles to and integral with one side of each of said abutments and adapted to be secured to the rim, an abutment member carried by and disposed at right angles with respect to the said side of each of said abutments and overlapping the rim, a holding arm extended at right angles to and from the other side of each of said slide abutments, said arm rabbeted on its inner face at each side thereof to provide a seat, a slide clamping member mounted over said

20. 25. 30. 35. 40. 45. 50. 55.

arm and common to seats thereon, and means for detachably clamping said member to its respective arm to secure a pair of slides thereto.

12. A projecting apparatus comprising a carrier including a rim, a series of spaced slide abutments disposed throughout said rim, a pair of apertured lugs extended at right angles to and integral with one side of each of said abutments and adapted to be secured to the rim, an abutment member carried by and disposed at right angles with respect to the said side of each of said abutments and overlapping the rim, a holding arm extended at right angles to and from the other side of each of said slide abutments, said arm rabbeted on its inner face at each side thereof to provide a seat, a slide clamping member mounted over said arm and common to seats thereon, means for detachably clamping said member to its respective arm to secure a pair of slides thereto, and electrically operated means successively engaging with said abutment members for intermittently shifting said carrier.

In testimony whereof, I affix my signature hereto.

ALPHEUS L. KISER.
